UNITED STATES PATENT OFFICE.

WILLIAM D. ANTRIM, OF GLOUCESTER CITY, NEW JERSEY, ASSIGNOR TO WELSBACK COMPANY, OF GLOUCESTER CITY, NEW JERSEY, A CORPORATION OF NEW JERSEY.

GAS HEATER.

1,406,523.

Specification of Letters Patent. Patented Feb. 14, 1922.

Application filed July 26, 1921. Serial No. 487,814.

To all whom it may concern:

Be it known that I, WILLIAM D. ANTRIM, a citizen of the United States, residing at Gloucester City, county of Camden, and 5 State of New Jersey, have invented a new and useful Improvement in Gas Heaters, of which the following is a full, clear, and exact description.

My invention relates to gas heaters or radiators and particularly to the type known as radiant heaters.

An object of my invention is to provide a heater with a plurality of heating units freely communicating at the top with a 15 common header.

A further object of my invention is such a heater wherein the header is used for igniting purposes and is composed of sections carried by the heating units.

20 Further objects will be apparent from a reading of the following description taken in connection with the accompanying drawings, in which:

Figure 1 is a longitudinal section of a 25 heater embodying my invention;

Figure 2 is a front elevation of one of the heating units.

Figure 3 is a side elevation of the element shown in Figure 2; and

30 Figure 4 is a front elevation of a modified element.

Referring to the drawings, the heater may be of any usual construction, having a base 1 of any suitable material, provided with 35 legs 2 at the corners. The base plate 1 is preferably formed so as to afford a chamber adjacent the bottom of the heater for the reception of a plurality of Bunsen tubes 3. These tubes are fed from the supply line 4, 40 controlled by a valve 5. Each of the tubes 3 feeds a heating unit 6. The units 6 are preferably of some suitable refractory material and are provided with a plurality of openings 7. At the upper end of each of the 45 elements is a section 8 which runs along an axis at right angles to the longitudinal axis of the elements so that when the elements are in vertical position, as shown, the sections 8 are horizontal. The sections 8 are

50 in free communication with the interior of the elements 6 and are arranged so that when the elements are set in the position shown in Figure 1 the ends of the sections abut, thus forming a continuous header 12 55 across the top of the elements.

There are two types of radiant heaters, one in which the radiants set close together, and another type in which the radiants are spaced apart at considerable distance. The latter type is shown in Figure 1 and the 60 sections 8 of the header are of sufficient length to permit of the spacing of the elements and at the same time form a continuous header; Figure 4 shows a radiant of the type wherein the elements are placed 65 close together, that is to say, wherein the elements touch each other. The radiant shown in Figure 4 is substantially the same as that shown in Figures 2 and 3, except the section across the top of the unit does not extend 70 beyond the body section. The unit shown in Figure 4, however, is provided at its ends 9 with an opening which communicates with a similar section on the adjacent units when assembled, thus forming a continuous section 75 header with units touching each other.

The function of the header, whether of the type shown in Figure 1, or that produced by assembling of a plurality of units 80 like that shown in Figure 4, is to afford a ready means of simultaneously igniting all of the burner elements from a common source such as a pyrophoric or other lighting device 10.

85 A section 11 of the header 12 may be formed of some suitable material and attached to the casing 13 of the heater or any other arrangement may be made, whereby the effect of the igniting device may be 90 transmitted to the first section of the header 12.

The last unit away from the igniting device is provided with a header section 14 95 which is closed at one end.

The arrangement above described has many advantages resulting from the construction and arrangement shown, residing principally in the fact that the header sections are integral with the heating units 100 and the header is thus provided upon the assembly of the units of the type shown in Figures 1 to 3 inclusive, or that shown in Figure 4.

Many other advantages will be apparent 105 to those skilled in the art.

Many changes may be made in the details of construction of the heater and also in the units without departing from the spirit of my invention.

I claim:

1. A heater of the class described comprising a casing, a supply line, a plurality of independent heating elements supplied from said line, and means by which said elements are ignited comprising a sectional header, each section being carried by one of said elements.
2. A heater of the class described comprising a casing, a supply line, a plurality of independent heating elements supplied from said line, and means by which said elements may be ignited comprising a horizontal header at the top of said elements and composed of registering sections, each section being carried by one of said elements.
3. A heater of the class described comprising a casing, a supply line, a plurality of independent vertical heating elements supplied from said line, and spaced apart from each other and an igniting header for said elements composed of a plurality of communicating sections each being horizontal and carried by one of said elements.
4. In a heater of the class described, the combination of a supply line, a plurality of vertical heating elements supplied from said line, a horizontal igniting header at the top of said elements, said header being composed of communicating sections carried by said elements.
5. In a heater of the class described, the combination of a casing, a supply line, a plurality of heating elements operatively connected with said supply line and held in position in said casing and an igniting header for said elements carried by said elements.
6. In a heater of the class described, the combination of a casing, a supply line, a plurality of heating elements operatively connected with said supply line and held in position in said casing and an igniting header for said elements comprising an integral part of a plurality of said elements.
7. In a heater of the class described, the combination of a casing, a supply line, a plurality of heating elements supplied by said supply line and held in position in said casing, said elements each having an interior chamber and communicating passages at the upper portion of said elements whereby an igniting header common to said elements is produced.

In testimony whereof, I have hereunto set my hand.

WILLIAM D. ANTRIM.
